Primary Examiner — Terry A Wallace(74) Attorney, Agent, or Firm — Joseph G. Chu; JCIP(57) CLAIM

I claim an ornamental design for a pestle, as shown and described.

DESCRIPTION

FIG. 1 is a perspective top view of a pestle showing our new design;

FIG. 2 is a left side elevation view thereof;

FIG. 3 is a right side elevation view thereof;

FIG. 4 is a front elevation view thereof;

FIG. 5 is a back elevation view thereof;

FIG. 6 is a top plan view thereof; and,

FIG. 7 is a bottom plan view thereof.
